[57] **CLAIM**

The ornamental design for a variable data imprinter, as shown and described.

DESCRIPTION

FIG. 1 is a front perspective view of a variable data imprinter, showing my new design;

FIG. 2 is a top plan view thereof;

FIG. 3 is a front elevational view thereof;

FIG. 4 is a side elevational view thereof viewed from the left of FIG. 2, the opposite side elevation being the mirror image thereof; and

FIG. 5 is a rear elevational view thereof.

The bottom of the imprinter is plain.
